G. H. RICKE,
SAFETY ATTACHMENT FOR FLYING MACHINES.
APPLICATION FILED AUG. 18, 1919.

Patented June 21, 1921.

FIG. 1.

FIG. 2.

FIG. 3.

FIG. 4.

INVENTOR
George H. Ricke
By John W. Strehli
ATTORNEY.

UNITED STATES PATENT OFFICE.

GEORGE H. RICKE, OF CINCINNATI, OHIO, ASSIGNOR TO AARON MCNEILL, OF NORWOOD, OHIO.

SAFETY ATTACHMENT FOR FLYING-MACHINES.

1,382,599.

Specification of Letters Patent. Patented June 21, 1921.

Application filed August 18, 1919. Serial No. 318,299.

To all whom it may concern:

Be it known that I, GEORGE H. RICKE, a citizen of the United States, residing at the city of Cincinnati, in the county of Hamilton and State of Ohio, have invented certain new and useful Improvements in Safety Attachments for Flying-Machines, of which the following is a specification.

My invention belongs to that class of flying machines, known as "heavier than air machines," although it may be applied to any other class or style of flying machine.

It consists essentially in applying a buoyancy chamber or attachment to the machine, provided with a door or doors underneath, which are always closed, but when the chamber is to be employed to retard the descent of the machine, they are opened by the operator, to allow the ingress of air to said chamber to buoy up the machine, and not allow it to descend rapidly, but to force it to flutter or drift and stop and retard its precipitation to the earth.

If the machine is disabled, it is possible for the operator to reach the earth safely, as he can use the chamber as a buoyancy means to assist in guiding the machine to making a safe landing.

The features of my invention and their advantages, will readily become apparent from the following specification.

In the accompanying drawing forming part of this specification:

Figure 1, is an isometric view of a flying machine with my attachment attached thereto,

Fig. 2, is a bottom view of the buoyancy chamber,

Fig. 3, is a sectional view, on the line 40 3-3 of Fig. 2, and

Fig. 4, is a similar view, without the gas container in the chamber.

In the drawing, 1 represents the body of the machine, supported on wheels 2, through any style of running gear; the head of the machine is marked 3 and the tail piece 4, and the motor of the machine is located at 5. The wings of the machine are marked 6. Further description of the flying machine is not needed here, as it is well known in the art, the attachment need only to be described, and its application to a flying machine.

The buoyancy chamber 11, is composed of a top piece 7 and a bottom piece 8, beveled or inclined at the ends to meet in a sharp

edge 9; these parts can be made of wire and cloth, canvas, duck or any strong material which will resist breakage or tear from the inflow of air. To the bottom 8, I hinge at 10 a door 12, which at its forward part or end is provided with a cable 13, connected to laterally disposed cables or pieces 18 which at their other ends slip through eyes 19 on the door 12; the cable 13 has a catch piece 14, which is connected by a latch or sliding bolt (not shown) to the body of the machine, near to the operator, where it can be conveniently reached. The buoyancy chamber is attached to the wings 6 and body 1, by the standard 15, two of which are connected to the outside of the wings 6, at each side of the body 1 and two are connected to the wings and body adjacent to the body itself. They may be made of aluminum wire, ratan, tubes, or any strong supporting means, very light and not cumbersome and may be attached to the parts in any suitable manner. In order to strengthen the buoyancy chamber, I place a series of broken wires 16 around the same.

The buoyancy chamber 11, may be made as shown in Fig. 4, or I may place therein a gas bag 20 of any shape, in the present instance, in Fig. 3, showing one of cylindrical shape, formed like an elongated link or loop, (see dotted lines in Fig. 2) placed on the inside edge or periphery of the chamber 11. I may form the chamber 11 of any contour and also the gas bag 20. The gas bag can be filled or emptied in the usual manner. The buoyancy chamber may be attached to the flying machine in any approved manner, but in such a way that it will not hamper the speed of the machine needed for flying purposes and remaining in the air, as a certain amount of speed is needed for this purpose.

Machines of this character, by reason of accident or inadvertence, or by a mistake of the operator, or from a defect in the machine itself, often tilt or become unstable, and tend to dip downward at the front; often being precipitated to the earth, before the operator can regain control, in many cases this is impossible to do, even if he were capable of doing so under certain circumstances and conditions. In order to prevent many of these accidents and mishaps, and regain control of the machine, or keep it from being precipitated to the earth, I have devised the buoyancy chamber which I employ over the

top of the machine. In case the operator finds it necessary to stabilize his machine or prevent its dipping and in case he must make a landing by reason of the machine not 5 operating properly, he can pull the cable 13 which unloosens the door 12 at the bottom of the buoyancy chamber, so that the air will rush into said chamber and thus have a tendency to buoy the machine and prevent its 10 too rapid descent; the chamber acting on the order of a parachute.

In order to make this buoyancy chamber more effective, I may, if desired, employ a gas bag as herein described, which will add 15 still more to the buoyancy of this chamber.

By using this invention, many accidents may be prevented and the operator will feel more secure and be encouraged and satisfied in the use of the machine.

20 By the use of my attachment, the flying machine can be used to advantage in teaching the art of flying, as the student is not apt to be injured, and he feels a certain degree of safety is provided for him.

25 My attachment will also be advantageous

to machines of this character used for ordinary commercial purposes in flying for short distances by amateurs.

It will be understood that this attachment will be connected to the machine in such a 30 manner that the strength of the machine and its flying properties will not be impaired.

What I claim as new and my invention, and desire to secure by Letters Patent, is:

An attachment for flying machines of the 35 class described, comprising a buoyancy chamber, said buoyancy chamber rigidly attached to the flying machine and being a component part thereof, and formed of spaced walls, terminating in pointed edges 40 and means for strengthening the same, an auxiliary gas bag on the inside of the buoyancy chamber hugging the edge thereof, and a door in said chamber, and means for opening and closing said door. 45

In testimony whereof, I affix my signature at Cincinnati, Ohio, this 16th day of August, 1919.

GEORGE H. RICKE.
